UNITED STATES PATENT OFFICE.

HENRY HAROLD READ, OF LONDON, ENGLAND.

PACKING CASE.

1,427,633.

Specification of Letters Patent. Patented Aug. 29, 1922.

Application filed November 12, 1921. Serial No. 514,749.

To all whom it may concern:

Be it known that I, HENRY HAROLD READ, of 84 Cranley Gardens, Muswell Hill, London, N. 10, England, a British subject, have 5 invented new and useful Improvements in or Relating to Packing Cases, of which the following is a specification.

This invention relates to packing cases and more particularly to wooden packing 10 cases wherein the sides and ends are constituted by a series of parallel boards and which may be bound internally or externally by strips of hoop iron. In such cases contiguous boards of an end or side have here- 15 tofore been usually secured together by means of nails passing from one board to the next diagonally across the plane of contact and even if the ends and sides be strengthened by means of hoop iron binding 20 strips they are liable to be stove-in during transit and owing to the splintering of the boards by the nails it is often impossible to repair the damage without opening the case.

It is the object of this invention to provide 25 improved means for connecting together the boards forming the sides or ends of the case whereby the case will be strengthened and its contents rendered less liable to pilfering during transit.

According to the present invention the contiguous edges of boards forming the sides or ends of a packing case are connected 30 together by means of angle plates in each of which one branch is disposed between the contiguous edges of two adjacent boards and is secured to the edge face of one of the boards whilst the other branch is secured to the inner or outer face of the contiguous 35 board. Preferably the angle plates are dis- 40 posed in alignment transversely of the boards and are slotted so as to permit a hoop iron binding strip to be passed through all the angle plates so as to underlie the second mentioned branch, said binding strip 45 being independently secured to the surface of the boards.

The angle plates and binding strips may be secured to the boards by means such as are described in my specification Serial No. 50 487,855.

The invention will be described with reference to the accompanying drawings of which Figure 1 is a plan of a portion of one side of a packing case, Figure 2 is a sectional elevation on the line 2-2 of Figure 1 and

Figures 3 and 4 are elevations of two forms of angle plates before bending.

To one edge face of each of three boards *a*, *b* and *c*, of one side of a packing case, is secured by means of nails *d* or the like one 60 marginal end portion *e* of a short strip *f* (Figure 3) of hoop iron or the like, said strip *f* being slotted transversely as at *g* and said slot *g* being disposed in line with the upper surface of said board *a*, *b* or *c*. The 65 strips *f* are so arranged that when the boards *a*, *b*, *c* are placed edge to edge as shown in Figures 1 and 2 the slots *g* are in alignment transversely of the boards *a* *b* *c* and a strip of hoop iron or the like *h* is threaded 70 through the slots *g* in succession and is secured by nails *j* or the like to the surface of the boards *a*, *b*, *c*. The outer marginal end portion *k* of each strip *f* is then bent over at right angles (along the line A-B Figures 75 3 and 4) so as to overlie the strip *h* and the board (such as *b*) adjacent to that (such as *a*) to which the end portion *e* is secured and a nail *m* or the like is driven through said strips *f* and *h* into the underlying 80 board *b*.

If desired the heads of the nails *j* and *m* may be soldered over and to the underlying strips *f* and *h* respectively as shown at *n* and *o* to the right of Figures 1 and 2 and the adjacent portions of the strips *f* and *h* may be soldered together as at *p* and *q*.

As shown in Figure 4 the strip *f* is rectangular in shape and the portion *k* has two or more holes *r*, *r* for the reception of nails 90 such as *m*. The ends of the binding strip *h* may simply be bent over and nailed to the edges of the outer boards or the strip *h* may serve to connect together adjacent sides or ends of the packing case and form a continuous band around the case. The strip *h* and marginal end portions *k* may be disposed either inside or outside the packing 95 case, as desired.

By this means a packing case of particularly strong construction is obtained.

I claim:—

1. A packing case of the kind set forth wherein the contiguous edges of boards forming the side or ends of the case are 105 connected together by means of angle plates in each of which one branch is disposed between the contiguous edges of two adjacent boards and is secured to the edge face of one of said boards whilst the other branch is 110

secured to one face of the contiguous board.

2. A packing case as claimed in claim 1 wherein the angle plates are disposed in alignment transversely of the boards and are slotted so as to permit a hoop iron binding strip to be passed through all the angle plates so as to underlie the second mentioned branch, said binding strip being independently secured to the surface of the boards.

10 3. A packing case having its boards connected by angle plates, one member of which is secured between adjacent boards and its other member overlying one of the said boards, and fasteners securing the said mem-

bers to the board, the heads of the fasteners 15 overlying said member and soldered thereto.

4. A packing case having its boards secured together by a band, and angle plates slotted at the junction of their members, the angle plates having one member secured between adjacent boards and its other member overlying one of the boards, the band extending through the slots of the angle plates and under the overlying members of the angle plates, and fasteners, the heads of which 20 overlie the band and the overlying member of the angle plate and soldered thereto.

HENRY HAROLD READ.
